UNITED STATES PATENT OFFICE.

JOHN F. MARTIN, OF MARSHALL, MICHIGAN, ASSIGNOR OF ONE-HALF TO
WALLACE E. MARSTON, OF SAME PLACE.

DESIGN FOR A BROOM-HOLDER.

SPECIFICATION forming part of Design No. 34,788, dated July 16, 1901.

Application filed April 8, 1901. Serial No. 54,954. Term of patent 14 years.

To all whom it may concern:

Be it known that I, JOHN F. MARTIN, a citizen of the United States, residing at Marshall, in the county of Calhoun and State of Michigan, have produced a new and original Design 5 for a Broom-Holder, of which the following is a specification.

This invention relates to a new and original design for a broom-holder; and the essential feature resides in the design as illustrated 10 in the accompanying drawings, wherein—

Figure 1 is a perspective view of a broom-holder embodying the features of the design. Fig. 2 is a transverse vertical section of the 15 same.

The numeral 1 designates a hollow body, which is of semicircular form and has a reduced vertical projection 2 extending therefrom, with opposite upwardly-converging concave side edges 3, extending to a rounded apex 4. The body 1 and projection 2 have a 20 marginal right-angular projection 5 extend-

ing rearwardly therefrom. On the front face of the body 1 are members 6 of the same contour as but smaller than the said body and its 25 projection and provided with lower forwardly-extended right-angular projections 7 at the lower portions thereof, the said members having the projections 7^a rising vertically and centrally therefrom. Extending forwardly 30 from the upper part of the body are posts or pins 8, which are located inside of the plane of the apices of the members 6.

Having thus described the invention, what is claimed as new is—

The design for a broom-holder, as herein shown and described.

In testimony that I claim the foregoing as my own I have hereto affixed my signature in the presence of two witnesses.

JOHN F. MARTIN.
